UNITED STATES PATENT OFFICE.

CHARLES F. HUNTOON, OF CHICAGO, ILLINOIS, ASSIGNOR TO CHICAGO RAILWAY EQUIPMENT COMPANY, OF CHICAGO, ILLINOIS, A CORPORATION OF ILLINOIS.

BODY-BOLSTER.

No. 851,753.

Specification of Letters Patent.

Patented April 30, 1907.

Application filed September 19, 1906. Serial No. 335,265.

To all whom it may concern:

Be it known that I, CHARLES F. HUNTOON, a citizen of the United States, residing at Chicago, Illinois, have invented a certain new and useful Improvement in Body-Bolsters, of which the following is a full, clear, and exact description, such as will enable others skilled in the art to which it appertains to make and use the same, reference being had to the accompanying drawings, forming part of this specification, in which—

Figure 1 is a side elevation of a bolster constructed in accordance with my invention; Fig. 2 is a cross sectional view taken on the line 2—2 of Fig. 1; Fig. 3 is a side elevation of a slightly modified form of my invention; and Fig. 4 is a view partly in end elevation and partly in section taken on the line 4—4 of Fig. 3.

This invention relates to bolsters for railway rolling stock, and has for its object to provide a body bolster that can be constructed of commercially rolled forms and which will possess the requisite degree of strength to enable it to withstand the strains to which it is subjected.

Referring to Figs. 1 and 2 of the drawings which represent the preferred form of my invention, 1 designates the top plate of the bolster, and 2 designates angles which are connected to the underneath side of said top plate with their horizontal legs or flanges projecting in opposite directions, the vertical legs of said angles being comparatively long and forming the side walls of the bolster. The bottom plate of the bolster consists of a rolled member 3 of special form provided with parallel upwardly extending flanges 4 located some distance inwardly from the side edges of said member, as shown in Fig. 3. The vertical legs of the angles 2 are telescoped inside of the upwardly extending flanges on the member 3 and are connected thereto by rivets 5, thereby forming a substantially box-shaped girder which is of simple construction and possesses a great degree of strength.

Preferably, the bottom member 3 is bent upwardly from the central portion of the bolster toward the opposite ends of the bolster and thence extends parallel to the top plate 1, so that the bolster is of greatest depth at its central portion from which point

it diminishes gradually in depth toward the end portions E which are of about one-half the depth of the central portion. The vertical legs of the angles 2 are sheared to conform to the shape of the member 3 and at the end portions of the bolster, said vertical legs are of approximately the same depth as the upwardly projecting flanges 4 of the member 3.

The bolster is provided with a center bearing 6 and side bearings 7 which are connected to the member 3 by rivets 9 located outside of the upwardly projecting flanges 4.

In Figs. 3 and 4 I have shown a slightly modified form of my invention in which the angles 2 terminate adjacent the straight end portions E of the bolster, the top plate 1 contacting with the upper edges of the vertical flanges 4 of the member 3 and said top and bottom member being connected together by rivets 10 which extend through cast fillers 11 interposed between the top plate 1 and bottom member 3 outside of the flanges on said member, as shown in Fig. 3, and at the right-hand side of Fig. 4.

While I have herein shown my invention as consisting of a body bolster it is obvious that a truck bolster could be constructed in substantially the same manner without departing from the spirit of my invention.

It will also be observed that instead of using the special rolled member as a bottom compression member, the arrangement of the parts could be reversed, and said special rolled member used as a top or tension member. In truck bolster construction a special rolled member would preferably be used as a top compression member and the plate 1 as the bottom or tension member.

Having thus described the invention, what is claimed as new and desired to be secured by Letters Patent is:

1. A box-shaped bolster having a member in the form of a rolled member provided with projecting flanges located some distance inwardly from its side edges; substantially as described.

2. A bolster consisting of a plate member, side walls located some distance inwardly from the side edges of said plate member, a rolled member of approximately the same width as the plate member, and projecting flanges on said rolled member which are con-

nected to the side walls of the bolster; substantially as described.

3. A bolster consisting of a plate member, angles connected thereto, a rolled member provided with projecting flanges located some distance inwardly from the side edges thereof, and means for connecting said flanges to the vertical legs of the angles fastened to the plate member; substantially as described.

4. A bolster consisting of a top plate, angles connected to the underneath face of said plate with their horizontal legs projecting in opposite directions, a rolled member having upwardly extending flanges located some distance inwardly from the side edges of said member and embracing the vertical legs of the angles that are secured to the top plate, and fastening devices passing through said flanges and angles; substantially as described.

5. A bolster consisting of a top plate, side walls located some distance inwardly from the side edges of said top plate, a rolled member of approximately the same width as the top plate and provided with flanges which are connected to the side walls of the bolster, and a center bearing connected to said rolled member by fastening devices which pass through the same outside of the flanges thereon; substantially as described.

6. A bolster consisting of a top plate, side walls, a bottom plate consisting of a rolled member provided with upwardly projecting flanges which contact with the top plate at the end portions of the bolster, and means for connecting said rolled member and top plate together; substantially as described.

7. A bolster consisting of a top plate, a bottom plate consisting of a rolled member provided with upwardly projecting flanges, said rolled member being spaced away from the top plate at the center of the bolster and bent upwardly to engage the top plate at the end portions of the bolster, and fillers interposed between said top plate and rolled member at the end portions of the bolster; substantially as described.

8. A bolster consisting of a top plate, angles connected to said top plate to form the side walls of the bolster, a rolled member provided with upwardly projecting flanges which are secured to the vertical legs of said angles, said member being bent upwardly so that its flanges will contact with the top plate at the end portions of the bolster, fillers arranged between said top plate and rolled member on each side of the flanges on said member, and fastening devices extending through the top plate, fillers and rolled member to connect said parts together; substantially as described.

9. A car bolster in which one of the members is a special rolled beam having flanges arranged perpendicular to the web portion and located some distance inwardly from the side edges of said web portion; substantially as described.

In testimony whereof I hereunto affix my signature in the presence of two witnesses, this 12th day of September 1906.

CHARLES F. HUNTOON.
